W. C. Wright.
Machine for Folding and Measuring Cloth.

No. 11,145.

Patented Jun. 20, 1854.

UNITED STATES PATENT OFFICE.

WM. C. WRIGHT, OF BOSTON, MASSACHUSETTS, ASSIGNOR TO JAS. F. WHITTEMORE,
RICH'D. MARTIN, AND WM. C. WRIGHT.

FOLDING AND MEASURING CLOTH.

Specification of Letters Patent No. 11,145, dated June 20, 1854.

To all whom it may concern:

Be it known that I, WILLIAM C. WRIGHT, of Boston, in the county of Suffolk and State of Massachusetts, have invented certain new and useful Improvements in Machines for Folding and Measuring Cloth, and that the following description, taken in connection with the accompanying drawings, hereinafter referred to, forms a full and exact specification of the same, wherein I have set forth the nature and principles of my said improvements, by which my invention may be distinguished from others of a similar class, together with such parts as I claim and desire to have secured to me by Letters Patent.

The figures of the accompanying plate of drawings represent my improvements.

Figure 1 is a front elevation of my machine for folding and measuring cloth. Fig. 2 is a rear elevation of the same. Fig. 3 is an end view. Fig. 4 is a plan of the supporting platform or table and one folder, and Fig. 5 is a top view of the machine with the platform and folding table removed.

With most of the machines with which I have been able to become familiar for folding and measuring cloth the folding has been accomplished by moving folders or by delivering rollers set in a carriage which traverses the table reciprocatingly and deposits the cloth in layers of equal length. As I learn from examination of some of these machines and from the opinion of others, who have seen them in operation, these machines will not always or under all circumstances fold and measure accurately the cloth which is passed through the machine, as the effect of the moving folders is very variable upon the cloth sometimes and the rollers in the traversing carriages do not always deliver evenly. By my improved machinery the folding and measuring are unerringly and accurately done, and the essential features of my machine are a moving table formed of a segment of a cylinder and having a reciprocating rotary motion imparted to it, the length of which motion may be adjusted for different lengths of folds, said table operating with a pair of guiding folders working alternately to form successive folds of the cloth, and a pair of adjustable holders at each end of the traversing table to hold the folds as they are made, these holders being arranged so as to be lifted up, at the time the end of each fold

is approached, and shutting down upon the same as soon as the table begins to reverse its motion.

In the drawings *a a a a* in the several figures represents the framework of the machine, *b b* is a platform sustained upon the top of a portion of this framework, and supporting the standards in which rest and turn the journals of the roller *c c*, which contains the cloth to be folded and measured. Near the front edge of the platform *b b*, is an elongated slot *d d*, made of such dimensions as to accommodate the greatest width of cloth to be folded and having an adjustable guide *e e* at each end by which the slot may be made narrower to accommodate the cloths of lesser width. The guides *e e* may be confined in any desired position, by means of the slots and set screws, shown at *f f*, that operate in a manner which will readily be understood by inspection of Fig. 4.

g g, Figs. 1, 2, 3 and 4, is the moving folding table, formed of a segment of a cylinder and of sufficient width to be applicable to the cloths of the greatest width. This table is supported on the upper end of the radial arm *h h*, and its braces *i i*, the lower end of said radial arm being connected to the rocker shaft *k k*, Figs. 1, 2, 3 and 5, the journals of which have proper bearings in the lower part of the framework, as shown in the drawings. The radial arm *h h*, by being vibrated, imparts a reciprocating rotary motion to the folding table *g g*, and the vibrations of said arm are effected by means of the connecting rod *l l* from the crank *m*, said connecting rod being arranged between the radial arm and crank, as shown in Figs. 1 and 2, and said crank being revolved by being attached to the end of the revolving shaft *n*, resting and turning in bearings in the lower part of the framework, as shown in Figs. 1, 2, 3 and 5. On the center of the shaft *n* is a larger wheel *o*, which engages with the pinion *p* on the crank or driving shaft *q q*, and through the connection thus established between the shaft *n* and *q q*, the former is made to revolve. The length of vibrations of the radial arm *h h*, and consequently of the sweep through which the folding table traverses forward and back, may be varied by varying the length of the crank *m*, and this may be effected by making the end of the connecting rod *l l*, which is connected to the crank *m*, adjustable in a

slot r of the same by means of the clamp screw s in a manner which will be readily understood by examination of Figs. 2 and 3. The object of thus varying the traverse motion of the folding table is to vary the length of folds in the cloth according to the desire of the manufacturer.

The end of the cloth to be folded being conducted down from the roller c , through the slot d , is passed underneath the rectangular guiding folders t t t — t t t and confined under one of the elongated holders u u u — u u u , arranged at each end of the folding table, so as to operate with said table as nippers. These two guiding folders t t t are arranged so as to turn in bearings at opposite ends of the framework of the machine, as shown in the drawings, and operate alternately, so as to guide the cloth only against the top of the table and under each of the two holders u u u , alternately, but they have nothing to do with determining the length of the folds, this, as before suggested, being effected by the movements of the folding table. These guiding folders are kept at their inner edges (when they are operating to guide the cloth) near the surface of the folding table by means of the spiral springs arranged as shown in Figs. 1 and 2, and they are alternately relieved from the cloth or table, when not wanted to guide the former, by the following combination of mechanical devices: An arm r , r projects at an obtuse angle with the plane of the folders, and from the rear of each the same, as shown in Figs. 1 and 2, and these arms are connected by the rods w , w to the lower ends of the two diverging levers x , x , which turn on proper pins or fulcra in the connecting rod y , y . The edges of the shorter arms of these levers x , x , bear against the two sides of the central cleat z , as shown by dotted lines in Fig. 1, so that these arms may turn upon their fulcra in one direction or so that their lower ends may approach each other, but may not be turned in the other direction, and by this arrangement when the connecting rod y , y is made to vibrate it will alternately by its motions through the medium of the said levers x , x , rods w , w , and arms r , r , raise the folders from the cloth as above suggested. The vibrations of the rod y , y are connected with the motion of the rocker shaft h , h , and consequently with the movement of the folding table, as will be readily comprehended, by means of the crank a' on one end of said rocker shaft, as shown in Fig. 1, and by reason of this connection the folders will always be lifted at the proper time whatever variation may be made in the movement of the folding table for the purpose of making different lengths of folds. The holders u u u , &c., are always kept down upon and

grip the folds with the exception of the moment when a new fold is being guided under them by the folders, when they are lifted for an instant and immediately descend again to hold the folds. These holders are narrow rectangular frames, as shown in the drawings, turning a little on journals which rest in adjustable right angular supports b b b b ', the horizontal arms of which are slotted so that they may be confined to the underside of the folding table, as shown in Figs. 1 and 2, by means of the confining screws c' , c' , this adjustment being necessary, as will readily be perceived, in order to provide for different lengths of folds. The gripping edge of the holders is kept down upon the folds by means of the rods d ', d ', d ', d ' connected at one end to a projecting arm e ' e ' of said holders, its other end moving in a guiding hole in the sector shaped block f ' on the rocker shaft. A spiral spring g ', g ' on each rod d ', d ', d ', d ' bears at one end on the periphery of the said block, its other end pressing against a nut h ', confined in any proper position on said rods d ', d ', so as to keep the holders constantly on the folds unless when relieved from the same, as above suggested, and so as to accommodate the accumulating pile of folds. The lifting of the holders, so that each new fold may be guided under the same, is effected by means of a pin or stud i ', arranged on one edge of each holder, and at or near its front, which stud moves at the proper time over a cam k ', k ', hung on a support l ', l ' fixed on one of the inner corners of each of the folders, said cam being curved so as to secure the requisite degree of lift. This cam is arranged so as to tilt upward and allow an easy escapement of the pin i ' over its back by being supported on a pin m ' in the supports l ', but it is kept from moving downward by a lateral arm which rests on a ledge of the support l ', as shown at n ' in Figs. 1 and 2—and a spring o ' may be used to prevent its flying up, the operation of which will be understood by inspection of the drawings.

In order to remove the cloth when folded from the folding table, it is necessary to lift the folders and holders altogether from the same and this is effected as follows: A treadle lever p ', p ' has a fulcrum at one end on the framework, and at its other end it has chains or cords q ', q ' which connect it to the lower ends of the diverging levers x , x , before referred to as operating the folders, and by depressing the treadle by the foot these folders will be lifted entirely from the cloth as desired. Another chain r ' from said treadle lever works a cross lever s ', s ' having a proper fulcrum in the radial arm h , h , and from the opposite end of said lever, a cord t ', t ' depends and passes around a fixed pulley u ', to the lower ends of two

rods v' v'' , the upper ends of which rod are connected to the arms e' , e'' of the holders, so that from what has been before explained it will be seen that the depressing of the 5 treadle will raise the two folders and two holders and entirely disengage them from the cloth, and it may then be removed from the table with perfect ease and without disturbing the folds.

10 Having thus described my improvements, I shall state my claim as follows:

What I claim as my invention and desire to have secured to me by Letters Patent is—

15 1. Making the folding table of a machine for folding and measuring cloth, to move with a reciprocating motion so as to make the folds and determine their length and also the making said motion adjustable in order to change the length of the folds to 20 be made and measured.

2. I claim the combination of the moving

folding table operating as above specified with the guiding folders and the elongated holders to each side of the table for folding and guiding the cloth to be folded and 25 holding it as herein above set forth.

3. I claim making the said holders adjustable upon the ends of the folding table so as to accommodate different length of folds as herein above set forth. 30

4. I claim relieving the cloth when folded from the folders and holders so that it may be removed from the folding table by raising all of them simultaneously by means of the treadle connected to the said folders and 35 holders through the mechanism herein above described or in any other way substantially similar.

W. C. WRIGHT.
